UNITED STATES PATENT OFFICE.

THOMAS J. LINDSAY, OF LAFAYETTE, INDIANA, ASSIGNOR OF ONE-HALF
TO DIETRICH H. LOHMAN, OF SAME PLACE.

BICYCLE-FRAME.

SPECIFICATION forming part of Letters Patent No. 619,322, dated February 14, 1899.

Application filed January 15, 1898. Serial No. 668,754. (No model.)

To all whom it may concern:

Be it known that I, THOMAS J. LINDSAY, a citizen of the United States, residing at Lafayette, in the county of Tippecanoe and State 5 of Indiana, have invented certain new and useful Improvements in Bicycle-Frames, of which the following is a specification.

The principal object of my present invention is to provide in the construction of a bicycle-frame an inclosing casing for the chain, which shall be embodied in and form a part 10 of said frame; and it consists in the construction and arrangement of parts whereby this object is accomplished, hereinafter more particularly described and claimed.

Referring to the accompanying drawings, which are made a part hereof and on which similar letters and numerals of reference indicate similar parts, Figure 1 is a side elevation of a bicycle embodying my present invention; Fig. 2, a detail side elevation of that portion of the frame wherein my said invention principally resides, certain portions thereof being shown in section; Fig. 3, a view, partially in top plan and partially in horizontal section, of the hanger and immediately adjacent parts as seen from the dotted line 3 3 in Fig. 2; and Fig. 4, a transverse sectional view as seen from the dotted line 4 4 in Fig. 2.

The bicycle illustrated in the drawings is that which embodies a certain driving-gear formerly invented by me; but, as will be readily understood, it is also applicable to the ordinary or any other desired gearing and only requires to adapt it thereto slight changes in form without material difference in construction.

As above indicated, the frame in its general construction and arrangement is or may be substantially of any form desired. The hanger A, however, which is carried by the ordinary frame members 1 and 2, has two tubular projections a, extending rearwardly toward the hub of the rear wheel, and to these projections the forward ends of two tubes B B are connected. These tubes not only form a portion of the frame, but also the horizontal portions of an inclosing casing for the chain. The construction and arrangement of the

gearing and its relation to the frame and casing parts are illustrated in Fig. 3. The ordinary frame member 3 has a structure C upon its lower end, which is rigid therewith and forms a part of the frame, and has two tubular projections c c, to which the other ends of the tubes B B are connected, as best shown in Fig. 2. A part C² is mounted in the structure C, (on the opposite side thereof to the projections c c, which receive the tubes B B,) and said part C² is capable of adjustment 60 telescopically relatively to said part C. Upon the outer end of the structure C² is a cap C', which covers the otherwise open space and is held in place by screws c'. The end of the shaft of the rear wheel passes through openings in the sides of the part C², and when said shaft is adjusted by means of the set-screws s in adjusting the tension of the chain the part C², because of its telescopic character, is also moved correspondingly. The hanger A 70 has a plate A', which is provided with ears a', and these extend over the edge of the hanger A and are secured to said hanger by screws a².

As will be readily seen, in my construction 75 the tubes B not only form a portion of the frame of the bicycle, but also constitute an inclosing casing for the chain. This arrangement produces a very strong, rigid, and durable structure and utilizes the chain-inclosing casing as a part of the frame itself and in a way which gives added strength and rigidity to the frame as a whole and particularly to that portion upon which the strain of the propelling power comes.

Having thus fully described my said invention, what I claim as new, and desire to secure by Letters Patent, is—

The combination, in a bicycle-frame, of the members 1, 2 and 3, the hanger and housing A having the projecting tubular portions a, a, the plate A' having the ears a², by which it is connected to said hanger, the structure C also forming a housing secured to the member 3, and having the tubular projections c, c, 95 on its front side, the cap C' secured over the open rear side of the part C², said part C² telescopically mounted in the rear end of the

part C, and the tubes B B secured in and connecting the projecting tubular portions *a*, *a*, and *c*, *c*, of the hangers A and C, whereby a rigid frame is secured and a chain-casing provided capable of ready adjustment, substantially as set forth.

In witness whereof I have hereunto set my

hand and seal, at Indianapolis, Indiana, this 10th day of January, A. D. 1898.

THOMAS J. LINDSAY. [L. S.]
